UNITED STATES PATENT OFFICE

WILBUR N. SQUIRES, OF JOPLIN, MISSOURI, ASSIGNOR TO HYDRAULIC DEEP WELL PUMP COMPANY, OF JOPLIN, MISSOURI, A CORPORATION OF MISSOURI

PUMP

Application filed September 16, 1927. Serial No. 219,922.

My invention relates to pumps for raising liquid, and while the specific embodiment which I shall describe is employed in the pumping of oil from oil wells, it is to be understood that such embodiment and use are illustrative and not limiting.

The pump of my invention relates more specifically to that class of pumps wherein a combined motor and pump unit is disposed 10 in the liquid to be pumped and is operated by reciprocating columns of liquid preferably but not necessarily contained in two concentric pipes as disclosed in my co-pending application, Serial No. 159,896, filed January 8, 1927, upon which the present application is an improvement.

It is highly desirable in pumps of this class which are adapted to be disposed in wells so deep that operation by the usual sucker rod 20 is difficult, to employ a minimum of piping or other material and to this end it is desirable, to employ the discharge line as a container for one of the operating columns of liquid. Since the pump is disposed at the bottom of 25 a long string of pipe from whence it is difficult and expensive to raise it, it is advisable to make it of the minimum number of operating parts and those of such a character that they are not liable to failure or wear to a 30 detrimental extent during the life of the device. Along with the simplicity of operating parts I have aimed to secure simplification of structure to the end of reducing cost of manufacture and rendering the device reliable and easy to operate.

To the above ends I have adopted a simplicity of fundamental design in that I employ a motor piston operated positively in alternate directions with a pump plunger operating in one direction to take in the liquid and in the other direction to discharge the liquid. In other words the motor piston is double acting and the pump piston is single 40 acting. While this is the simplest design and it is one which I prefer, reasons for which will be more apparent later, I do not wish to be limited solely to this design since my invention comprehends certain improvements 45 in pumps that may be applied to other designs

than that which I have elected here to show and describe.

Of the two concentric pipes the inner one preferably communicates with the top of the motor piston to permit pressure in said inner 55 pipe to perform the discharge stroke of the pump, and the outer pipe, or more specifically, the space between the two pipes communicates with the bottom of the motor piston to permit pressure in said outer pipe to make the 60 suction or intake stroke of the pump, and this column in the space between the pipes is the one which receives the discharge of oil or other liquid on the discharge stroke of the 65 pump.

I prefer to close off the one end of the pump cylinder so that upon the discharge stroke of the pump a vacuum is created in said closed end, but I may open said end of the pump cylinder to the discharge line and 70 by using a motor piston of larger area than the pump piston secure the desired force for making the suction stroke of the pump by the differential areas thus provided. This provides a relatively large force for the discharge stroke and less force for the intake stroke which is in accordance with actual requirements. It is desirable to employ as light a pressure as possible on the discharge column for two reasons, first, because this pressure is imposed directly on the check valves 75 of the pump and second, because for commercial thickness of wall the outer tube or conduit is not inherently as strong to withstand internal pressure as in the inner pipe or 80 conduit merely because of difference in their diameters. Hence while the employment of differential areas of the pump and motor pistons would permit me to dispense with the packing about the piston rod this is not 85 wholly without drawback in deep well operation.

Within the limits of the dimensions available in and within the limitations imposed by a deep well, I prefer to employ the packing for keeping the end of the pump cylinder sealed against the rod and permit a vacuum to be drawn in the closed cylinder end during the discharge stroke.

I employ a packing around the stem or rod 100

between the motor piston and the pump piston to separate the two working cylinders from each other and to seal the upper end of the pump cylinder. Hence on the downward stroke of the pump the space above the pump piston is evacuated. Since the tendency to create a vacuum at this point may induce leakage, or may be conducive of the formation or release of gas, which would 5 10 15 20 25 30 35

would then be trapped on the upward stroke, I have provided a discharge check valve leading from said space above the pump piston preferably through the piston so that any gas or liquid which might enter the space will be displaced from such position.

I contemplate also the provision of a discharge passageway from the closed end of the pump cylinder to the outside of the entire pump, this passageway being controlled by a check valve or valves opening outwardly. The space between the piston and the packing i. e. the closed cylinder end may open freely into the outside of the well if so desired to permit idle inflow and outflow of liquid. 20 25 30 35

In that event the passageway through the piston may be eliminated.

A restricted passageway at this point provides an additional function, namely that the upward stroke of the moving pistons and 30 35 40 45 50 55

their connecting rod is checked as the stroke nears completion. That is to say, any liquid or gas which is trapped at the upper end of the stroke and discharged through restricted ports provides a cushion.

55 The same function is desirable for checking the movable system towards the end of the downward stroke and to this end I have provided a liquid check or dash pot for decelerating the moving system as it approaches 60 65 70 75 80 85 90 95 100 105 110 115 120 125

the end of its downward stroke. This liquid check comprises preferably a short open ended cylinder with restricted discharge ports adjacent the lower end of the main motor cylinder and adapted to receive a more or less loosely fitting plunger mounted on the rod adjacent the main motor piston as the main motor piston approaches the end of its stroke. It is desirable to have the check piston and cylinder of smaller diameter than the main motor piston so that motion in the reverse direction may be started promptly and without developing excessive pressure and also so that the wear at this point will not affect the tightness of the main cylinder and piston.

In this manner I have provided a fluid check for the end of the stroke of the moving system in each direction. Obviously either one or both may be dispensed with, without dispensing with certain of the other advantages of my invention herein described and claimed.

130 In a pumping system of this character it is desirable to provide means for permitting the pump and connecting pipes to be pulled

out of the well without being required to lift both columns or either column of liquid.

According to my invention I have provided a readily operable drain valve for draining both columns into the well when it is desired to pull the pump. The means which I provide in the preferred form of my invention comprises a telescopic joint in the inner concentric pipe, the telescoping parts over-running or closing drain ports leading from within the inner pipe to the outside of the outer pipe. Obviously within my invention these ports may lead only from the space between the pipes to the outside of the outer pipe since the inner pipe may be drained into the outer by disengaging the telescoping connection. 70 75 80 85 90 95 100 105 110 115 120 125

Also instead of having this connection in the inner pipe it may be contained in the outer pipe. For the sake of simplicity in pulling the pump the telescopic or other joint is made in the inner pipe so it may first be withdrawn without the requirement to move or raise the outer pipe. 85 90 95 100 105 110 115 120 125

In the pumping of oil a certain amount of gas is encountered. The gas which is evolved in the well and arises within the casing does not interfere with pumping but the gas which is evolved within the pump or the liquid columns tends first to cause the pump cylinder to become gas bound and second tends to impart to the liquid columns particularly the discharge column an undesired compressibility or elasticity preventing the exertion of full pressure upon the bottom of the motor piston to make the intake stroke. The first tendency can be overcome by making the stroke long relative to the bore so as to gain a very high compression ratio. 90 95 100 105 110 115 120 125

The second difficulty can be overcome by a modification herein shown wherein a differential motor piston is employed, so that the force upon the bottom area of the motor piston structure may be made ample to overcome the force upon the upper face of the motor piston structure even if only a low pressure is exerted through the discharge column. Thus if so much gas is contained in the discharge column as to render it quite compressible the pump may still be operated without requiring an excessively large jack cylinder for that column. In fact by selection of the proper areas the jack cylinder for the discharge column may be entirely eliminated and the reciprocation of the wider column solely employed to operate the pump. 110 115 120 125 130

In addition to the above features of novelty numerous improvements in details of construction are embodied in the form of pumps which are herein illustrated and described. I do not intend to be limited to these details except as they are recited in the appended claims.

Now in order to acquaint those skilled in the art with the manner of constructing and 130

operating my invention, I shall describe in connection with the accompanying drawings a few specific embodiments of the same.

In the drawings:

5 Fig. 1 is a longitudinal vertical section through a pump embodying my invention;

Fig. 2 is a section taken at right angles to Fig. 1 on the line 2—2 showing the upper part of the pump in section;

10 Fig. 3 is a view taken on line 3—3 of Fig. 1 showing the lower part of the pump in section;

Fig. 4 is a cross sectional view of a modified form of the invention;

15 Fig. 5 is a cross section taken on the line 5—5 of Fig. 1;

Fig. 6 is a section taken on the line 6—6 of Fig. 1;

20 Fig. 7 is a section taken on the line 7—7 of Fig. 1;

Fig. 8 is a cross section taken on the line 8—8 of Fig. 1;

Fig. 9 is a cross section taken on the line 9—9 of Fig. 2;

25 Fig. 10 is a cross section taken on the line 10—10 of Fig. 2.

Fig. 11 is a cross section taken on line 11—11 of Fig. 2.

Fig. 12 is a longitudinal section of a modified form of the pump shown in Figs. 1 to 11, inclusive.

Fig. 13 is a cross sectional view taken on line 13—13 of Fig. 12.

30 Fig. 14 is a diagram of a modified form of the pump shown in Figs. 1 to 11, inclusive, and

Fig. 15 is a similar diagram of a like modified form of the pump shown in Figs. 12 and 13.

40 These respective sections being taken and viewed in the direction indicated by the arrows accompanying the section lines.

The pump of my invention is adapted to be submerged in the liquid to be pumped and 45 it is connected to jack or pulsator mechanism by means of the discharge pipe line 11 and the inner pipe line 12. These two pipe lines are connected to a mechanism for reciprocating the columns of liquid which are contained

50 within the respective pipes, as is explained in my prior copending application and in my copending application, Serial No. 220,728, filed Sept. 20, 1927, which I have recently developed. The body of the pump 13 is sus-

55 pended on the end of the outer pipe 11. The body of the pump is made up of two main units, the upper one for the motor mechanism, and the lower one for the pump mechanism. The shell of the pump is made of two

60 sections of seamless steel tubing 14 and 15. The upper section 14 is shrunk upon a semi-steel cylinder casting 16, having the cylindrical bore 18 and being grooved or fluted to provide four longitudinal passageways be-

65 tween the wall of the tubing 14 and the wall

of the cylinder casting 16. The ridges or lands which run longitudinally of the cylinder casting 16 are machined to size and said casting is either shrunk or pressed into place within the tube 14. The upper end of the tube 14 is reduced and threaded as indicated at 19 for connection to a coupling 20, which has a threaded portion 21 cooperating with the threaded portion 19 and has an inwardly extending flange 22 forming a shoulder for engaging the flange 23 of the drain flange fitting 24. The drain flange fitting 24 has a stud or telescoping member 25 adapted to cooperate with another fitting which I term the drain flange cap 26, said member 26 having a depending skirt or flange 27 telescoping with the portion 25 of the drain flange member 24. The lower edge of the skirt or telescoping member 27 is flared outwardly to assist in guiding these parts into telescoping relation. The member 26 is provided with a shoulder which is grooved to receive a ring of hard Babbitt metal 28 which seats flat upon the top or end surface of the member 25 to form a tight closure between the bore 30 of the member 26 and the bore 31 of the member 24.

The drain flange member 24 has longitudinal passageways 32 extending therethrough and communicating with like longitudinal passageways 33 formed in the wall of the cylinder 16, the lower ends of said passageways 33 communicating with radial drill holes 34 extending out through the webs or lands on the wall of the cylinder 16 to provide drain passageways normally closed by the seating of the shoulder 28 upon the end 29.

The upper surface 29 is provided with a series of circular ridges, such as would be made by a shallow cut with a threading tool, the surface of the ring of Babbitt metal 28 being flat. This arrangement of circular grooves provides a form of labyrinth packing, the ridges of the one surface tending to bite into the face of the other surface. The column of pipe 12 rests upon the member 26 and it in turn rests upon the drain flange member 24 so that the two parts are held together under great pressure.

The pipe 12 is connected to the drain cap fitting 26 by means of a threaded pipe coupling 35 of well known construction.

The coupling 20 which holds the drain flange member 24 upon the end of the cylinder is in turn connected to the external pipe line 11 through a reducing coupling 36.

The drain flange member 24 is held in register with the upper end of the cylinder 16 through the use of dowel pins 37, 37 (see Fig. 10). Preferably a thin copper gasket is interposed between the member 24 and the upper end of the cylinder 16 to maintain a tight joint between these parts.

The flange 23 has four perforations 38 registering with the grooves 39 or the longi-

130

tudinal passageways formed by these grooves with the wall of the member 14.

The lower end of the steel tube 14 is counterbored as indicated at 40 to receive the 5 cushion cylinder member 41. The lower end of the counterbored portion 40 is internally threaded as indicated at 42 and this threaded portion cooperates with the corresponding reduced threaded portion 43 forming the 10 upper end of the tube 15. The tube 15 has a cylinder member 44 therein, this cylinder member also having grooves such as 45 along the sides of the same forming fluid passageways. The cylinder member 44 is likewise 15 machined off on its peripheral surface and pressed into place or secured in place by shrinking, as described previously in connection with the cylinder member 16.

Preferably the ends of the cylinders 44 20 and 16 where they are required to make tight joints, namely at the upper end of the cylinder 16 and at the lower end of the cylinder 44 are brazed or otherwise integrally united to the corresponding cylinder walls of the 25 tubes 14 and 15 to provide tight gasket seats and gaskets are employed at these points.

The lower end of the tube 15 has a reduced threaded portion 46 to which is threaded the upper end of the valve cage holder member 47.

20 The cushion cylinder member 41 comprises a small cylinder member 48 having a cylindrical bore, the mount or upper edge of the cylinder 48 being notched away to provide free passageway from the chamber formed 25 in the counterbore 40 into the lower end of the cylinder member 16 leaving only the posts 49 extending upwardly in contact with the lower end of the cylinder member 16. Thus it can be seen that the chamber formed in 40 the counterbore 40 communicates with the interior of the lower end of the cylinder 16 below the motor piston therein and communicates also with the space between the pipes 11 and 12 through the passageways 39 externally of the motor cylinder 16 but within 45 the shell of the pump formed at this point by the tubing 14.

The motor piston 50 fits tight in the bore 18. It is stopped in its motion upwardly 50 by the shoulder which is formed between the bore 31 and the bore 18 of the cylinder. It is to be observed that the bores 30 and 31 are of the same size, and they are both smaller than the bore 18 or the bore of the pipe 12. 55 At its lower end the piston 50 has an extension 51 to which is connected the cushion piston and coupling member 52, this piston 52 being threaded internally to receive the upper threaded end of the connecting rod 53. 60 The piston 52 fits fairly closely within the cylinder 48 so as to trap liquid therein. The cylinder member 48 has an inwardly extending circular flange 54 adapted to act as a positive stop for the motor piston 50 and 65 connected parts. A rod 53 passes down

through the body of the member 41 and through a bushing 55 of anti-friction metal which maintains a substantially tight joint with the piston rod 53. The bushing 55 is preferably made of bronze or other anti-friction metal. It has a flange 56 secured to the bottom of the wall 57 in which the body thereof is seated. The member 41 has a chamber 58 therein communicating with the upper cylinder portion 48 and the chamber 75 58 communicates with the exterior through restricted passageways or ports 59, which control the rate at which liquid is driven out of the cylinder 48 by the check piston 52.

The member 41 has a cylindrical flange 80 or barrel 60 formed integral with the wall 57, the lower edge of this circular flange or barrel being adapted to seat upon the end 43 of the lower tube member 15. A series of four 85 posts 61 extend inwardly from the circular flange or wall 60 and they seat upon the lands or ridges formed on the interior of the lower cylinder member 44. The member 41 is preferably held in place as by dowel pins 62, shown in Fig. 6. Now it will be seen that 90 the passageways formed by the grooves 45 along the lower cylinder 44 communicate with the chamber in the counterbore 40 through the spaces between the lower wall 57 of the member 41 and the circular barrel or flange 95 60, as indicated at 63.

The upper end of the pump cylinder 44 is counterbored to form a shoulder as indicated at 64 in Fig. 1, a bronze piston rod guide 65 being seated in the bore 66 of the pump cylinder 44 and having its head seating against the shoulder 64. Suitable packing 67 is seated in the counterbore and is maintained in place by the gland 68, the lower end of which enters the counterbore and compresses the packing 67, the flange of the gland 68 being held by suitable studs 69. The packing 67 thereby closes the upper end of the cylinder above the pump piston 70 which is connected to the lower end of the rod 53. Both of the pistons 50 and 70 are carefully ground to fit and provided with suitable metallic packing rings. The pump piston 70, as shown in Fig. 1, has a longitudinal bore 71 therethrough, the lower end of the bore terminating in a valve seat 72, normally closed by a spring held check valve 73 of the poppet type. The valve 73 has a stem 74 guided in the cap or cage 75, which cap or cage is threaded to the lower end of the piston 70. The cap or cage 75 has a series of passageways therethrough to permit fluid escaping through the bore 71 and past the valve 73 to pass below the piston and the cage 75. The upper end of the bore 71 is closed by the rod 53 but the bore 71 communicates with radial drill holes or passageways 76 communicating in turn with longitudinal drill holes or passageways 77 leading to the top of the piston 70 and thereby commun- 115 120 125 130

cating at all times with the closed end of the cylinder 44. The purpose of the passageways 77, 76, 71 and the valve 73 is to permit the escape of any fluid which enters the closed end of the cylinder 44 to escape on the upward or suction stroke of the pump, as will be explained more in detail later.

The lower end of the pump section above described has a valve cage 78 secured thereto by means of the valve cage holder 47, previously referred to. This member 78 contains the discharge check valves 79, 79 which are hard steel balls. Below the discharge check valve cage member 78 is mounted the inlet 15 check valve cage 80 containing the intake check valve which is a hardened steel ball 81. The intake valve cage 80 comprises a tubular member 82 having a flange 83 at the upper end thereof, which fits within the holder 47, 20 said holder 47 having an inwardly extending flange 84 cooperating with the flange 83. A hardened seat member 85 is pressed into a counterbore in the intake valve cage member 80 and the upper end of the intake valve cage 25 82 fits against the lower end of the discharge valve cage 78 and is held in engagement therewith with a fluid tight fit through the medium of the holder 47. Likewise the upper end of the cage member 78 is held fluid tight against 30 the lower end of the cylinder and shell members 44 and 15.

The upper end of the bore 86 of the intake valve cage above the seat 85 is enlarged to provide a communicating passageway between two sets of longitudinal passageways 35 in the member 78. The cage member 78 has a central circular opening 87 therein, as can be seen in Figs. 1 and 7. This opening 87 communicates with two circular passageways 40 88, 88 which extend down to the chamber 89 formed above the inlet check valve 81.

The discharge check valves 79, 79 are housed in chambers 90, 90 formed in the lower end of the member 78, these chambers communicating at their upper ends with the passageways 91, 91 which extend up into communication with the passageways formed by the grooves 45 leading up to the chamber in the counterbore 40.

50 The chambers 90, 90 below the check valves 79, 79 are closed by the hardened steel seat members 92, 92 which are threaded into the bottom of the chambers 90 and which have passageways communicating with the chamber 89. Thus it will be seen that when the piston 70 is raised suction will be created in the lower end of the cylinder 44 and fluid will be drawn up through the bore 86 raising the check valve 81 passing into the chamber 89, 55 then up through the passageways 88, the central passageway 87 and into the lower end of the pump cylinder. Upon downward motion of the piston 70 thereafter the check valve 81 is seated against its seat 85 and liquid is discharged from the lower end of the cylinder 60

der 44 through the central opening 87 to the passageways 88 into the chamber 89, thence up through the valve seat members 92 raising the check valve 79, through the chambers 90, up through the passageways 91, and thence 70 up through the passageways formed by the grooves 45 inter-communicating with the chamber in the counterbore 40, thence up through the passageways 39 outside the cylinder 16, thence up through the passageways 75 38 through the flange of the drain flange member and up into the space between the pipes 11 and 12 constituting the discharge line.

It is to be understood that the pipes 11 and 12 are connected to a suitable pumping jack or head mechanism, which applies pressure alternately to said pipes for the purpose of reciprocating the motor piston 50 and which is provided with a suitable let-off valve for 80 letting off from the column in the pipe 11 the liquid discharged at each discharge stroke of the pump.

When pressure is applied to the pipe 12 pressure on the pipe 11 is released. Thereby 90 the piston 50 is forced down in the cylinder 16 thrusting the rod 53 and the pump piston 70 downwardly. Downward motion of the piston 70 evacuates the space in the upper end of the pump piston 44 below the packing 67 95 and discharges liquid through the connections previously described into the discharge pipe 11.

As the piston 50 approaches the lower end 100 of its stroke the check piston 52 enters the cylinder 48 and traps therein and in the chamber 58 a part of the liquid, thereby decelerating the motion of the moving parts to prevent pounding. The liquid which is thus trapped is forced out through the restricted openings 105 59. The liquid which is forced out by the piston 50 in its downward motion goes up through the passageways 39, as above described, to the discharge pipe 11 and joining the discharge from the pump cylinder. 110

When pressure is released on the pipe 12 pressure is applied by the head mechanism to the pipe 11. Since the discharge check valve 79 intervenes, this pressure cannot be imposed upon the lower end of the piston 70, but is imposed upon the lower end of the piston 50 and the piston 50 is thereby forced upwardly. Thus the suction stroke of the piston 70 is performed, drawing in liquid from the well through the bore 86 passing by check valve 81 and up into the pump cylinder. Any gas or liquid which has leaked into the closed end of the cylinder 44 will be expelled through the drill holes 77, 76, central bore 71 and check valve 72 of the pump piston 70. 115 120 125

Obviously the discharge check valve for discharging fluids trapped in the fluid end of the cylinder may discharge to the outside of the pump by providing a discharge passage-way such as shown at 95 in Fig. 4, said pas- 130

sageway being controlled by suitable valve check 96 permitting the passage of liquid and gases outwardly, but preventing inflow of the same. It is also to be understood that 5 free passageway between the interior of the closed end of the cylinder 44 and the exterior of the pump may be provided for flow of fluids in both directions within the scope of my invention.

- 10 If it is desired to raise the pump from the well the central pipe line 12 is first pulled upwardly to disengage the telescoping parts 27 and 25. Raising of the part 26 above the part 24 first opens the drain passageways 32 15 from the inside of the pipe 12 to the edge of the pump and thereafter disengagement of the parts 24 and 26 permits the liquid on the outside of the pipe 12 likewise to drain to the exterior of the pump. Thus the pump may 20 be pulled without being required to lift the liquid in the pipes 11 and 12.

Where considerable gas is encountered it may be desirable to provide the differential motor piston structure shown in Figs. 12 and 25 13. In this structure an additional cylinder is interposed between the main motor cylinder 16 and the drain flange member 24 with its coupling 20.

A section of steel tubing 100 has a fluted 30 cylinder member 101 pressed thereunto as previously explained and the ends are brazed to provide tight gasket seats. The flutes 102 form passageways communicating with passageways 39 below and passageways 38 above. 35 The bore 103 of the cylinder 101 is smaller in diameter (for example 2") than the bore 18 (for example 2 $\frac{7}{8}$ ") of cylinder 16 to provide the desired differential area. The diameter of cylinder bore 18 may be made larger 40 if desired.

A piston 104 fits the bore 103 and it is joined by a rod 105 to the piston 50 in bore 18.

The steel tube 100 is counterbored and threaded as indicated at 106 to thread upon 45 the threaded part 19 of tube section 14. Likewise the upper end is reduced and threaded as indicated at 107 to cooperate with the threaded part 21 of coupling 20.

The space between the pistons 104 and 50 50 is dead space. As such it is subjected to contraction and expansion by the movement of the piston structure. Preferably but not necessarily I provide a relief connection for discharging any fluid which may enter as by 55 means of a longitudinal passage 108 extending by way of radial drill holes 109 from said space down to the valve 73. Since both spaces namely the space between the two pistons 50 and 104 and the space above piston 70 are contracted and expanded simultaneously fluid 60 will be expelled from both. Obviously said space between pistons 50 and 104 could be drained by a check valve passageway such 65 as 95 through the side walls of the pump as

shown in Fig. 4 or by an open passageway to the outside of the pump.

The operation of this form of the pump is apparent from the explanation heretofore made. 70

As heretofore stated instead of closing the upper end of the pump cylinder to prevent pressure of the discharge column from being exerted on top of the pump piston, I may open said upper end of the pump cylinder and leg 75 providing a differential area between the top surface of the pump piston and the bottom surface of the motor piston the suction stroke may be made. This construction may be employed in the form of pump shown in Figs. 80 1 to 11, by merely omitting the packing closing the upper end of the pump cylinder and increasing the diameter of the motor piston as indicated diagrammatically in Fig. 14.

Likewise the pump shown in Figs. 12 and 85 13 may be arranged for differential operation by omitting the packing for the upper end of the pump cylinder 44 and providing differential areas between the pump piston 70 and the motor piston 50 as indicated in Fig. 15. 90 The drain passage 108—109 and check valve 73 are not affected and remain the same. Otherwise the details of construction are not altered.

I do not intend to limit my invention to 95 the details shown and described except as they are recited in the appended claims.

I claim:

1. In combination, a motor cylinder, a double acting piston therein, a pump cylinder, a 100 piston therein, a rod connecting the pistons, means to apply pressure alternately to opposite sides of the motor piston, and means for checking the motion of the moving parts at each end of their stroke, said means comprising chambers within which the pistons move, said chambers having restricted outlets and means for trapping fluid in said chambers during the corresponding strokes. 105

2. In combination, a mechanism comprising 110 a motor cylinder having a piston, means for applying pressure alternately to opposite sides of the piston, a pump cylinder having a piston, a rod connecting the pistons, means providing a tight joint between the rod and one end of the pump cylinder, a discharge passage way leading from the other end of the pump cylinder into communication with the lower side of the motor piston, a passageway extending from the closed end of the 120 pump cylinder to the outside of the mechanism, and a check valve controlling said last named passageway, said check valve permitting fluid to pass from the closed end of the pump cylinder. 115

3. In a pump of the class described, the combination of a motor cylinder, a piston therein, a pump cylinder, a piston therein, said pistons being of different areas and being connected together, a passageway leading 125 130

to the upper end of the motor cylinder, a discharge passageway leading into the lower end of the motor cylinder and to the upper end of the pump cylinder, the lower end of the pump cylinder having intake and discharge check valves and said end of the pump cylinder communicating with the discharge passageway through the discharge check valve.

4. In a pump of the class described, the combination of a pump cylinder, a first motor cylinder and a second motor cylinder all in alinement, the second motor cylinder being of a diameter smaller than the diameter of the first motor cylinder, said motor cylinders being joined end to end, connected pistons in said cylinders, the pump cylinder having an inlet and a discharge check valve, a discharge pipe communicating with the discharge valve and with the lower end of the first motor cylinder, and a second pipe communicating with the upper end of the second cylinder.

5. In combination, an outer pipe, a fitting secured to the lower end of the outer pipe, said fitting providing a cylindrical flange extending upwardly substantially axial of said pipe, a port including a portion extending longitudinally through said flange, said port opening to the exterior of the outer pipe, an inner pipe carrying a shoulder adapted to seat over said port and having a flange about said shoulder for embracing the first mentioned flange, said flanges being separable.

6. In combination, a first tubular sleeve having a counterbore, a fluted cylinder pressed into the reduced portion of said sleeve, a second tubular sleeve having a fluted cylinder pressed into the same and having a stud adapted to be threaded into the counterbore of the first sleeve.

7. In combination with the elements of claim 6, a motor piston in the first cylinder, a pump piston in the second cylinder, a rod connecting said pistons, a packing disposed about the rod at the end of the second cylinder which is adjacent to the threaded joint, and a follower for restraining said packing.

8. In combination with the elements of claim 6, a piston in the first cylinder member, a piston in the second cylinder member, a rod connecting the pistons, a checking cylinder in said counterbore, and a piston member adapted to enter said checking cylinder at one end of the stroke of the motor piston.

9. In combination with the elements of claim 6, of a coupling member threaded to the free end of the first tubular sleeve, said coupling member having an inwardly extending flange, a telescoping member embraced by said flange and having a flange lying under said first flange to hold the telescoping member endwise in engagement with the adjacent end of the first cylinder member, there being a drain passageway extending longitudinally

through the telescoping member through a portion of the first cylinder member and out through the first tubular sleeve, and a second telescoping member cooperating with the first telescoping member for shutting off said drain passageway, said second telescoping member having a fluid pressure pipe connected thereto and having a passageway communicating with the upper end of the first cylinder member.

10. In combination with elements of claim 6, a sleeve member threaded to the outer end of second tubular sleeve and having an inturned flange, an inlet member having a cylindrical member embraced by the inturned flange, and having an outwardly extending flange in endwise engagement with the inturned flange, said inlet member having a longitudinally extending inlet passageway, an inlet check valve controlling said passageway, a cylindrical valve cage disposed within said sleeve member and held in endwise engagement between the second cylinder member and the inlet member, said valve cage having passageways therethrough communicating with the flutes on the second cylinder member, check valves controlling said passageways and said valve cage having passageways communicating with the lower end of the second cylinder member and extending into communication with said first mentioned passageways below said check valves.

11. In combination with the elements of claim 6, a valve cage disposed endwise in engagement with the remote end of the second cylinder member and having two pairs of passageways therethrough, the first pair communicating at one end with the interior of the said second cylinder member and the second pair communicating with the flutes outside the second cylinder member, check valves in said latter passageway, an intake member disposed in endwise engagement with the valve cage, said intake member having a longitudinal passageway controlled by an inlet check valve and a threaded sleeve member having an inturned flange co-operating with flange on the intake member for holding the intake member and the valve cage permanently in endwise alignment with the second cylinder member, said sleeve member being threaded upon the second tubular sleeve.

12. In combination, a pair of concentric pipes, a combined pump and motor element suspended from the outer pipe, an inner telescopic member secured to the outer pipe and an outer telescopic member secured to the inner pipe and embracing the inner member, said inner telescopic member having a passageway extending to the outside of both pipes and having its inner end closed by the outer member.

13. In a pump of the character described, an outer casing enclosing a motor cylinder, a piston therein, a pump cylinder, a piston

- therein, a rod connecting said pistons, the pump cylinder having inlet and discharge passageways communicating with one end thereof, check valves for said passageways, 5 the discharge passageway of the pump cylinder beyond the check valve therefor communicating with one end of the motor cylinder, a discharge pipe also communicating with said end of the motor cylinder and with the 10 discharge passageway, a pipe communicating with the other end of the motor cylinder, said pipes being adapted to be filled with liquid columns to be reciprocated for operating the 15 motor piston, the other end of the pump cylinder being closed to the remainder of said pump and having a passageway leading to the exterior of the casing.
14. In a pumping mechanism, a hollow shaft, a fluted hollow shaft pressed into said 20 first mentioned shaft, the flutes forming passageways for the passage of fluid, and the inner shaft also constituting a passageway for fluid, means for reciprocating the fluid in one of the passageways and means operated 25 by the fluid in both passageways for forcing fluid through the other passageway.
15. A deep well pump including an outer casing extending to the bottom of a well, a motor piston and a pump piston at the bottom 30 of the casing, means connecting the two pistons, means for reciprocating the pistons, and a fluid check within the casing and adjacent one of the pistons for checking the motion of the pistons as they approach one end of the 35 stroke.
16. In combination, a pair of hollow shafts one within the other, a combined pump and motor element carried by one of said shafts, said shafts being adapted to contain liquid, 40 and a normally closed passageway extending longitudinally of the shafts opened by relative movement between said shafts for draining liquid out of said shafts.
17. In combination, an outer shaft, a fitting 45 secured to the lower end of said shaft, said fitting providing a flange extending upwardly substantially axial of said shaft, a port through said flange, and opening on the exterior of the outer pipe, and an inner shaft 50 carrying a shoulder adapted to seat over said port to close the same, said port being opened by the relative movement between said shaft.
18. In a deep well pump, a motor element 55 at the bottom of a well, said element comprising two cylinders of different diameters, the smaller cylinder opening into and being connected to the larger cylinder, a piston in each cylinder, a connecting rod between the pistons, two columns of liquid for actuating 60 said motor element, one of said columns of liquid bearing against one of the pistons and the other column bearing against the other piston, the two pistons and the walls of the two cylinders forming a single chamber the 65 volume of which varies with the different po-
- sitions of the pistons, and a pump element controlled by said motor element for pumping liquid into one of said columns.
19. In a device of the class described, a power cylinder, a differential cylinder, and a 70 pump cylinder all in alignment, a power piston, a differential piston, and a pump piston connected for joint operation, the power cylinder and differential cylinder communicating with each other at one end, pipes for 75 defining hydraulic columns connected with the remote ends of the power cylinder and the differential cylinder respectively, said pump cylinder having a discharge communicating with one end of the pipes and with the end of 80 the differential cylinder.
20. In a device of the class described, a differential hydraulic motor and a pump connected to said motor, said motor comprising a power cylinder, a differential cylinder of 85 larger diameter than the power cylinder in endwise alignment with the power cylinder, said cylinders having their adjacent ends connected, passageways for liquid communicating with the remote end of said cylinders, a 90 pump having a piston connected and operated by the differential motor and having a discharge communicating with one of said liquid passageways.
21. In a device of the class described, a differential motor, a cylinder for said motor having bores of different diameter communicating directly with each other and having their opposite ends open, a pump having a 95 movable piston and having a discharge delivering liquid into the open end of the larger bore of the cylinder.
22. In a device of the class described, a differential motor comprising two connected pistons of different diameter, a cylinder having communicating bores of different diameter for said pistons, an open-ended pump cylinder having its open end adjacent the open end of a motor cylinder and communicating with the bore of larger diameter thereof, a pumping piston in the pump cylinder connected with said motor pistons, said pumping cylinder being provided with a valved discharge communicating with the open bore of larger diameter and the passageways for liquid communicating respectively with the bore of smaller diameter than with the bore of larger diameter of the motor cylinder.
23. In a device of the class described, the combination of a first sleeve member, a fluted cylinder member disposed within the same, a second sleeve member having a releasable joint with said first sleeve member and having a fluted cylinder member disposed therein, the flutes in both of said cylinders forming continuous fluid passages, a spacing member disposed between said cylinder members, said spacing member forming a short checking cylinder opening into the adjacent end 120

- 125

of the first cylinder member, a motor piston in
the first cylinder member, a pump piston in
the second cylinder member, a rod connect-
ing the pistons, said fluid passages communi-
cating with the ends of the motor and the
5 pump cylinders, and means for trapping fluid
in the checking cylinder, said checking cylin-
der having a restricted outlet.

In witness whereof I hereunto subscribe
10 my name this 12th day of September, 1927.

WILBUR N. SQUIRES.
